SUTURE HOLDER AND DISPENSER

Edgar L. Ross, Los Angeles, Calif., assignor of
ten per cent to Joseph A. Parker, Los Angeles,
Calif.

Application February 6, 1950, Serial No. 142,605

5 Claims. (Cl. 206—63.3)

1

This invention relates to a holder and dispenser particularly adapted for use with wire sutures, the primary object of which is to permit the ready delivery of the sutures in straight, single lengths thus eliminating kinks, and consequent breakage of the delivered sutures.

A further important object of this invention is to provide a suture holder and dispenser which is relatively simple in design and construction and very easy to operate so that the handling of the sutures is minimized and the delivery thereof is accomplished with a marked saving in time and trouble.

Yet another object of this invention is to provide a suture holder and dispenser which lends itself to easy sterilization, either cold or by autoclave, and does not have to be sterilized after each use when employed for minor office surgery.

Another important object of this invention is to provide a suture holder and dispenser of the character described including a transparent container and a means for readily indicating the size of the suture wires therein.

And a further object of this invention is to provide a suture holder and dispenser comprising a vertical tube closed at its bottom end and open at its top, elongated sutures retained in said tube, clamping means retaining said sutures straight and in a bundle, resilient means urging said clamping means into engagement with said sutures, and means for raising said sutures in said tube to expose the upper ends thereof through the open top end of said tube.

These, together with various ancillary objects and features of the invention which will later become apparent as the following description proceeds, are attained by the device, a preferred embodiment of which has been illustrated by way of example only in the accompanying drawings, wherein:

Figure 1 is a side elevational view of the holder and dispenser illustrating the manner in which the sutures are wholly contained therein;

Figure 2 is a side elevational view similar to Figure 1 but illustrating the manner in which the upper ends of the sutures are exposed for dispensing;

Figure 3 is a sectional view taken substantially on the plane of section line 3—3 of Figure 1;

Figure 4 is a perspective view of the clamping means;

Figure 5 is a fragmentary end elevational view of the upper end of the holder; and

Figure 6 is a fragmentary vertical sectional

2

view through a modified form of the invention.

Specific reference will now be made to the drawings. In the several views in the accompanying drawings and in the following specification reference characters indicate corresponding elements throughout.

The holder and dispenser is generally indicated at 10 and comprises a transparent tube 12 which has an open top end 14 and a closed bottom end 16, the latter being provided with a relatively small aperture 18 therethrough. The tube 12 is preferably fabricated of a heat-resistant glass, such as Pyrex or the like, and includes a colored band or frosted area 20 adjacent its top end serving as an indicator for the length of the wire sutures retained in the tube.

Retained in the tube is a plurality of straight, wire sutures 22 aggregated in a bundle, the overall length of the wire sutures being only slightly less than the total length of the tube 12, the bottom ends thereof being spaced from the closed end 16 of the tube as at 24. A clamping means is provided for retaining the sutures straight and in a bundle, this clamping means comprising a pair of vertically spaced plates 26 and 28 pivotally interconnected at their vertical edges 30 by means of a pair of terminally pivoted links 32 and 34. As will be seen clearly from the drawings, the plates and the links in assembly embrace the bundle of sutures intermediate its ends within the tube 12.

Secured by means of a loop 36 to the bottom-most plate 28 is a cable 38, which may be fabricated of any suitable material but preferably nylon, the cable extending through the aperture 18 of the closed end 16 of the tube. Secured as by a loop 40 to the uppermost plate 26 is a further cable 42 which extends through a relatively short vertical slot 44 provided in the top end 14 of the tube. The cable 42 may be provided with a loop 46 intermediate its ends embracing the bundle of sutures as shown clearly in Figure 1.

To maintain proper tension on the clamping plates 26 and 28 so that they are urged at all times into positive engagement with the bundle of sutures, a coil spring 48 is provided which is disposed exteriorly of the tube 12 and which is terminally secured as at 50 and 52, by appropriate loops, to the free ends of the cables 42 and 38, respectively. The cable 42 is further provided with a knob or stop 54 disposed exteriorly of the tube 12 which is adapted to engage the side wall of the tube at the slot 44 to limit the downward movement of the bundle of sutures within the tube so that the bottom end of the sutures will

remain spaced from the closed end 16 of the tube as at 24 in their extreme retracted position thus preventing injury to these ends. A tab 56 may be secured to the cable 38 beneath the coil spring 48 to indicate the length and dimensions of the sutures within the tube.

In the modification illustrated in Figure 6, the construction of the tube 12, the disposition of the sutures 22 therein, and the attachment of the coil spring 48 to the free ends of the cables is exactly the same as that shown in Figures 1 to 5, however, the clamping plates 26 and 28 are eliminated. Accordingly, only a single cable 58 is provided which extends through the slot 44 at the top end of the tube and through the aperture 18 at the bottom end of the tube, the external portion thereof including the stop 54 engageable with the side wall of the tube at the slot 44 to limit the downward movement of the sutures therein. The portion of the cable 58 which is disposed interiorly of the tube includes a pair of loops 60 and 62 intermediate its ends which firmly embrace the bundle of sutures 22 at vertically spaced points. It is understood that the coil spring 48 will be terminally secured to the free end portions of the cable 58 to provide proper tension on the loops so that they will at all times firmly engage and embrace the bundle of sutures.

In use, either of the external portions of the cables 42 and 38, the cable 58, or the coil spring 48, are urged downwardly with the hand to assume the position shown in Figure 2 so that the upper ends 54 of the sutures become exposed and spread slightly so that an individual suture may be pulled out of the bundle, the suture being dispensed without any kinks and with a minimum of handling. The coil spring 48 applies such a tension to the clamping plates 26 and 28 or the loops 60 and 62 so that after the removal of one or more of the sutures, the remainder of the sutures are still retained in a tight bundle. Movement of the external portion of the cable or the coil spring 48 upwardly to assume the position shown in Figure 1 will effectively replace the bundle of unused sutures in the tube, the stop 54 engaging the side wall of the tube 12 at the slot 44 to limit the downward movement of the bundle of sutures so that the bottom ends thereof will not contact the closed end 16 of the tube but will be spaced therefrom as at 24 to prevent injury to these ends.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A suture holder and dispenser comprising a vertical tube closed at its bottom end and open at its top, elongated sutures retained in said tube, clamping means retaining said sutures straight and in a bundle, said clamping means including a pair of plates and links pivotally interconnecting the vertical edges of said plates, 5 said plates and links embracing said bundle of sutures, resilient means urging said clamping means into engagement with said sutures, and means for raising said sutures in said tube to expose the upper ends thereof through the open top end of said tube, said raising means including a cable, a slot in the top end of said tube and an aperture provided in the closed end thereof, one end of said cable passing through said slot and being secured to one of said plates, the other 10 end of said cable extending through said aperture and being secured to the other of said plates, a portion of said cable extending along the side wall of said tube and disposed exteriorly thereof.

2. The combination of claim 1, wherein said 15 resilient means includes a coil spring interposed in said external portion of said cable.

3. The combination of claim 2, and a stop 20 carried by said external portion of said cable adapted to abut the side wall of said tube at said 25 slot to limit the downward movement of said sutures in said tube.

4. A suture holder and dispenser comprising a vertical tube closed at its bottom end and open at its top, said closed end being provided with an aperture, a bundle of sutures in said tube, a slot 30 at the top end of said tube, a cable in said tube extending through said slot and said aperture, loops intermediate the ends of said cable embracing said bundle of sutures, and a coil spring 35 disposed exteriorly of said tube and terminally secured to the free ends of said cable.

5. The combination of claim 4, and a stop 40 carried by said cable and engageable with the side wall of said tube at said slot to limit the downward movement of said bundle of sutures in 45 said tube.
